(57) CLAIM

We claim the ornamental design for a container lid, as shown and described.

DESCRIPTION

FIG. 1 is a perspective view of a container lid in accordance with a first variant of said Design, in which the plug is in a closed position;

FIG. 2 is a rear view of the container lid shown in FIG. 1; FIG. 3 is a right side view of the container lid shown FIG. 1; FIG. 4 is a front view of the container lid shown in FIG. 1; FIG. 5 is a left side view of the container lid shown in FIG. 1; FIG. 6 is a top plan view of the container lid shown in FIG. 1; FIG. 7 is a bottom plan view of the container lid shown in FIG. 1; FIG. 8 is a perspective view of the container lid shown in FIG. 1, with an exemplary environmental container; FIG. 9 is a perspective view of a container lid shown in FIG. 1, in which the plug is in an open position; FIG. 10 is a rear view of the container lid shown in FIG. 9; FIG. 11 is a right side view of the container lid shown in FIG. 9; FIG. 12 is a front view of the container lid shown in FIG. 9; FIG. 13 is a left side view of the container lid shown in FIG. 9; FIG. 14 is a top plan view of the container lid shown in FIG. 9; FIG. 15 is a bottom plan view of the container lid shown in FIG. 9; FIG. 16 is a perspective view of the container lid shown in FIG. 9, with an exemplary environmental container; FIG. 17 is a perspective view of a container lid in accordance with a second variant of said Design, in which the plug is in a closed position;

FIG. 18 is a rear view of the container lid shown in FIG. 17; FIG. 19 is a right side view of the container lid shown FIG. 17; FIG. 20 is a front view of the container lid shown in FIG. 17; FIG. 21 is a left side view of the container lid shown in FIG. 17; FIG. 22 is a top plan view of the container lid shown in FIG. 17; FIG. 23 is a bottom plan view of the container lid shown in FIG. 17; FIG. 24 is a perspective view of the container lid shown in FIG. 17, with an exemplary environmental container; FIG. 25 is a perspective view of the container lid shown in FIG. 17, in which the plug is in an open position; FIG. 26 is a rear view of the container lid shown in FIG. 25; FIG. 27 is a right side view of the container lid shown in FIG. 25; FIG. 28 is a front view of the container lid shown in FIG. 25; FIG. 29 is a left side view of the container lid shown in FIG. 25; FIG. 30 is a top plan view of the container lid shown in FIG. 25; FIG. 31 is a bottom plan view of the container lid shown in FIG. 25; and, FIG. 32 is a perspective view of the container lid shown in FIG. 25, with an exemplary environmental container. The broken lines depict portions of the article that form no part of the claimed design.
